UNITED STATES PATENT OFFICE

2,617,031

ELECTROMAGNETIC RADIATOR

John T. Bolljahn, Washington, D. C.

Application December 6, 1944, Serial No. 566,938

1 Claim. (Cl. 250—33.63)

(Granted under the act of March 3, 1883, as
amended April 30, 1928; 370 O. G. 757)

1

This invention relates to the construction of radiators for electromagnetic transmission and is particularly directed to the problem of maintaining the desired operating characteristics with decreased physical size of the structure.

The radiator of the present invention is of the type in which an array of slots defined by apertures in a cylindrical member is employed to yield an omnidirectional field strength pattern circumferentially of the cylinder, and a somewhat compressed single lobe pattern in a longitudinal plane passing through the axis of the cylinder.

The invention is particularly intended for use in applications where small physical size of the radiator is of primary importance, as in aircraft installations.

The invention will be further described with reference to the exemplary embodiment shown in the drawings, in which

Fig. 1 shows an antenna of the present invention partly broken away to show the internal construction.

Fig. 2 shows a section on the line 2—2 of Fig. 1.

Fig. 3 shows a section on the line 3—3 of Fig. 1.

In the embodiment shown in Fig. 1, the radiating structure is formed by conducting tube 1 apertured to form two series of slots, 2 and 3. Six slots at equal angular spacing are provided in each series, all slots being of the same dimensions, their length being substantially a half wave long.

As will be understood, the slots are excited medially on each longitudinal edge and constitute radiating elements. The circular array gives a pancake-type beam whose sharpness is increased by employing the two series of slots to give a double array.

Such an array has been proposed wherein the slots are cut in a wave guide carrying TE₀₁ radiation, the field within the guide being distorted asymmetrically at each slot by conductors extending inwardly of the guide medially of each slot wall. The diameter of the radiator is determined by the wavelengths of the radiation, however, due to the fact that TE₀₁ excitation is required the guide cannot be smaller than 1.2195 λ , where λ is the operating wavelength.

It has been found that such a large diameter is unnecessary to secure the desired directional characteristics of the radiated field pattern, and that a structure of much smaller cross-section

may be employed and still maintain the desired field pattern. The invention is directed to a structure of this type.

It is an object of the invention to provide a radiator of the type described which is of small physical size and yet maintains the desired field pattern.

It is another object of the invention to provide a radiator of the type described which is of small physical size and yet maintains the desired field pattern and which is of such physical size that it may be conveniently installed in aircraft.

It is a further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

It is a still further object of the invention to provide a radiator of the type described which is of small physical size and yet maintains the desired field pattern and which is of such physical size that it may be conveniently installed in aircraft.

The invention described herein may be manufactured and used by or for the Government of

the United States of America for governmental purposes without the payment of any royalties thereon or therefor.

I claim:

An omnidirectional slot type radiator structure consisting of a cylindrical conductive sheet slotted longitudinally to define an array of parallel circumferentially spaced radiating elements having a length substantially that of a half wave at the operating frequency of the radiator structure, the inner diameter being less than .4065 the said wave length, a main two conductor line extending axially along the center of the cylinder, and radially extending connectors branching from the main line conductors at adjacent locations and terminating electrically at the inner surface of the cylinder at each longitudinal side of each slot centrally of its length, whereby the radiators

of the array are connected in parallel across the main line.

JOHN T. BOLLJAHN.
